Application November 22, 1948, Serial No. 61,445

19 Claims. (Cl. 93—8)

This invention relates to bag-making machines, and more particularly to a machine for inserting a sleeve in the valve of a valved bag.

It is now customary to package units of granular or powdered material, such as sugar, flour, cement and fertilizer, in lots of given weights, such as 100 lbs., in multi-layer paper bags that are provided with a sleeved valve in one corner to facilitate the filling and emptying and to prevent sifting of the bags. The so-called "valve" in these bags consists of an opening formed by turning in one of the corner edges of the top of a bag. A sleeve composed of a rectangular sheet is then folded over and inserted in the folded-in corner, with its inner end folded around the edge of the folded-in corner and its outer end extending laterally beyond the edge of the bag for a short distance.

The longitudinal edges of the sleeve, when in position, substantially coincide with and form a continuation of the top edges of the bag. When the sleeve is in position, the bag is then closed by sewing across the top of the bag and along the length of the sleeve, a closing strip preferably being folded over the top edges of the bag and the sleeve before the sewing operation. The free end of the sleeve may then be opened to admit a filling machine nozzle for the admission of a given quantity of material into the bag, and the bag is then closed by folding the free end of the sleeve over and tucking it into the corner notch formed by the valve in the bag.

At the present time, the manufacture of these bags is effected completely by machinery, with the exception of the insertion of the sleeve into the valve. The industry has machines for automatically making the bag, for folding in the corner of the bag to form the valve, and for sealing the bag after the sleeve has been inserted in the valve. The insertion of the sleeve into the valve, however, is effected by hand labor. Consequently, this particular step in forming the bag has been very costly in proportion to the other steps of manufacture.

Therefore, it is the primary object of the present invention to provide a machine for automatically inserting sleeves into valve bags.

It is another object of the invention to provide a machine for automatically forming individual sleeves from a long strip and then inserting the individual sleeves into valved bags.

It is a further object of the invention to provide a machine that has simplicity of design, economy of construction and efficient in operation.

Other incidental objects will become apparent from the subsequent description.

The foregoing objects and others ancillary thereto are, preferably, accomplished in accordance with the preferred embodiment of the invention, by a machine having a pair of opposed gripper rolls adapted to grip the opposite top edges of a bag to open the bag to spread and flatten the valve-forming fold, means for forming, pasting, folding and securing a sleeve to the valve portion while it is flattened by the gripper rolls, means for feeding and removing bags to and from said gripper rolls, and means for folding and smoothing the sleeved valve as the bags are withdrawn from the gripper rolls.

The novel features that are considered characteristic of the invention are set forth with particularity in the appended claims. The invention itself, however, both as to its organization and its method of operation, together with additional objects and advantages thereof,

will best be understood from the following description of specific embodiments when read in connection with the accompanying drawings, wherein like reference characters indicate like parts throughout, and in which:

- 5 Figure 1 is a top plan view of a machine in accordance with the present invention, parts being shown in cross section or diagrammatically or being omitted to effect a more complete understanding of the machine;
- 10 Figure 2 is a cross-sectional view taken on line 2—2 of Figure 1 and showing the bag-handling mechanism of the machine in side elevation;
- 15 Figure 3 is a front view in elevation, parts being omitted for better illustration of the bag-handling mechanism;
- 20 Figure 4 is a side view in elevation corresponding to Figure 2 of the complete machine;
- 25 Figure 5 is a fragmentary cross-sectional view taken on line 5—5 of Figure 1;

Figure 46 is a cross-sectional view taken on line 46—46 of Figure 45;

Figure 47 is a cross-sectional view similar to that of Figure 46 to show parts in different relation;

Figure 48 is a fragmentary side view in elevation of valve and sleeve hold-down springs carried by the creasing blade in operative position;

Figures 49, 50 and 51 are fragmentary top plan views of the modified folding blade shown in Figure 45 and illustrating the operation of the blade; and

Figure 52 is a view in perspective of the modified folding blade and valve hold-down arm.

Referring now to the drawings, specifically to Figures 1-3, the present invention comprises a machine, including a main frame 1 supporting a source of power, such as an electric motor 2, and a main drive shaft 3 that is driven from the motor 2 as by a chain 4 extending around a motor sprocket 5 and a drive shaft sprocket 6. A feed table 7 extends rearwardly from the frame 1 and is adapted to receive valve bags B, one at a time, for feeding to the machine.

The table 7 is provided with side rails 8, between which the bags B are positioned, and a longitudinal slot 9 to accommodate a bag pick-up lug 10 carried by an endless chain 11. The chain 11 is trained about a pair of sprockets 12 and 13, the latter of which is co-mounted on a shaft 14 with a sprocket 15 which is connected by a chain 16 to a sprocket 17 fixed on an auxiliary drive shaft 18 that is in turn driven through its sprocket 19 by a chain 20 that is trained about a sprocket 21 on the main drive shaft 3.

The table 7 is provided with a pair of transversely spaced openings 22 for the reception of the upper peripheries by a pair of drive rolls 23 which are mounted on the auxiliary drive shaft 18. Corresponding opposed drive rolls 23' and 23'', are respectively mounted on floating shafts 18' and 18'' immediately above and below the supply rolls 23. A gear 24 is fixed to the auxiliary drive shaft 18 and meshes with gears 24' and 24'' respectively on the upper and lower shafts 18' and 18''.

The upper and lower shafts 18' and 18'' are resiliently biased toward the auxiliary drive shaft 18 by spring mountings 25 and 25' respectively, so that the three sets of superimposed rolls are in peripheral engagement or spring biased against a bag between the adjacent rolls. The rolls 23 have their upper peripheries extending through the openings 22 to be positioned substantially at or very slightly above the level of the table 7 to readily accommodate the leading edge of a bag B as it is moved along the table 7 by the pick-up member 10.

The rolls 23 are driven in a direction so that their upper peripheries move forwardly and in the same direction as the member 10, whereas the rolls 23' and 23'' are respectively driven in the opposite direction. A pair of superimposed feed rolls 30 and 30' are spaced in front of the drive rolls 23 and 23' and at the same level. The feed rolls 30 are mounted on a fixed shaft 31, whereas the superimposed feed rolls 30' are mounted on a floating shaft 31' that is biased by a spring mounting 32 toward the shaft 31.

As best seen in Figure 3, the fixed shaft 31 carries a gear 33 that meshes with a gear 33' that is fixed to the shaft 31'. The fixed shaft 31 is reversibly driven by means of a gear 34 which is in engagement with a rack 35 that is carried by a cam follower 36 which is operated by a cam 37 mounted on the main drive shaft 3. The cam follower 36 is moved back and forth by the cam 37 and carries with it the rack 35 which drives the gear 34 and shaft 31 in reverse directions.

A pair of superimposed gripper rolls 40 and 40' are respectively mounted on shafts 41 and 41' immediately in front of the feed rolls 30 and 30' which feed and withdraw the bags B to and from the gripper rolls 40 and 40'. The gripper rolls 40 and 40' are driven in opposite directions by intermeshing gears 42 and 42' which are

fixed to their shafts 41 and 41' respectively. The gripper rolls 40 and 40' are also reversibly driven by a mechanism similar to the reversible drive for the feed rolls 30 and 30'. A gear 34' is fixed to the shaft 41 and is engaged by a rack bar 35' that is carried by a cam follower 36' that cooperates with a cam 37' that is also fixed on the main drive shaft 3.

The organization of the reversible drive for the gripper rolls is best shown in Figure 5, wherein it will be seen that the cam follower 36' comprises an elongated guide loop 43 surrounding a guide roller 44 journaled on the main drive shaft 3. A cam following pin 45 is carried at one end of the loop 43 to ride in a cam groove 46 formed in the face of the cam 37'. The cam groove 46 may be provided with any desirable configuration that will impart the desired movement and dwells to the rack bar 35'.

Whereas the rack bar 35, follower 36 and cam 37 are identical to the construction illustrated in Figure 5, but on the reverse side of the cam 37, the cam groove in the cam 37 will be of different configuration to the groove 46 in the cam 37' because it is necessary to impart a longer period of movement through the rack bar 35 to the feed rolls 30 and 30' than that required for the gripper rolls 40 and 40'. The rack bars are preferably guided in their contact with their respective gears by yokes 47 and 47', respectively, that extend around the top and sides of the bars and down the sides of the gears.

The gripper rolls 40 and 40' carry grippers or clamps 50 and 50', respectively, as best shown in Figures 2, 6 and 7. These gripper rolls and clamps are identical with the exception that they are in reverse relationship, and, for simplicity, only the roll 40' is shown in Figures 6 and 7. The clamp 50' is carried by a reduced portion 51 of a bar 52 that is slidably mounted diametrically of the roll 40', the reduced portion 51 extending through a slot 51' in the peripheral flange 40a of the roll 40'. The bar 52 has a series of slots 53 surrounding and slidable upon a corresponding series of bolts 54 that are carried by the roll 40'.

40 The bar 52 also includes a looped portion 55 having a slot 55' for freely surrounding the roll hub 40b to permit diametric movement thereof. A cup or other member 56 is carried by the bar for the reception of or abutment by a spring 57 that engages the inner periphery of the roll 40' to bias the bar 52 inwardly with the clamp 50' in engagement with the outer surface of the roll 40'. A cam following roller 58 is carried by the bar 52 for engagement with a cam 59 that is journaled on the hub 40b. The cam 59 is provided with a hump 60 and an arm 61 extending radially for fixing the cam hump 60 in angular relationship.

As the roll 40' is reversibly driven by the shaft 41', the spring 57 will tend to bias a clamp 50' against the periphery of the roll 40'. However, when the roller 58 abuts the cam hump 60, the bar 52 is forced outwardly against the spring 57 and the clamp 50' is spaced from the roll 40' to release and receive the edge of a bag B. In order to regulate the opening of the clamp 50' at a proper angle of movement by the roll 40', the arm 61 of the cam 59 is, preferably, adjustably secured to a bracket 62 supported by the frame 1. The bracket 62 has a slot 63 for the longitudinally adjustable reception of a bolt 64 carried by the arm 61 to vary the angular position of the arm 61 and the cam hump 60.

65 The feed rolls 30, 30', and the gripper rolls 40, 40' are driven in the same direction simultaneously by their reversible drives through the racks 35, 35'. Thus, the feed rolls 30, 30' receive the forward end of a bag B from the drive rolls 23, 23' and feed the bag forwardly to the gripper rolls 40, 40'. The feed rolls 30, 30' start their forward movement before the gripper rolls 40, 40' so that the gripper rolls are still stationary with their clamps 50, 50' open and in substantially abutting relationship, due to the cam humps 60, as best shown in Figures 2 and 9.

This position of the gripper rolls 40, 40' and clamps 50, 50' constitutes their feeding position or station, in which the clamps are adapted to receive the forward or top edges of the bag B. At the moment that the forward edges of the bag are inserted into the clamps, the rack 35' initiates the forward movement of the gripper rolls 40, 40' so that the rolls are then driven in the same direction and at substantially the same speed as the feed rolls 30, 30'. As soon as the gripper rolls 40, 40' move,

the clamps 50, 50' are closed, by moving off the cam hump 60, and grip the edges of the bag.

The gripper rolls 40, 40' and feed rolls 30, 30' are driven forwardly until the clamps 50, 50' are respectively positioned substantially on the horizontal planes of the axes of their rolls. This movement separates the edges of the bag B and it is opened thereby, the inward fold V, forming the valve, being spread out in a substantially flat condition, as best shown in Figure 8. This is the sleeving position of the gripper rolls 40, 40' as the valve flap V is flattened in a substantially vertical plane and adapted to receive a sleeve.

After a sleeve has been applied to the flap V, the reversible drive of the racks 35, 35' is initiated and the gripper rolls 40, 40' and feed rolls 30, 30' are rotated in the opposite direction, back of the feeding station or position, whereupon the bag B is released by the clamps 50, 50' and the movement of the gripper rolls 40, 40' is stopped, while the drive of the feed rolls 30, 30' is continued until the bag is discharged therefrom.

During the forward movement of the bag B by the gripper rolls 40, 40', its rear edge passes beyond the forward edge of the table 7 and by gravity drops below the level of the table 7. When the movement of the bag B is reversed, it drops to a lower guide 65, which directs it to the drive rolls 23, 23', and these latter rolls withdraw the bag from the machine and discharge it to a suitable receiving means, as shown in Figure 1.

The drive of the feed rolls 30, 30' and the drive rolls 23, 23' is correlated through the main drive shaft 3 and auxiliary drive shaft 18 with the drive of the pick-up member 10 so that this member is moved in timed relation with the feed rolls 30, 30'. The pick-up member 10 is adapted to move a bag B forwardly to the drive rolls 23, 23' which will continue to move the bag forwardly so that the front edge of the bag will reach the feed rolls 30, 30' at substantially the moment, or just prior thereto, of reversal of the drive of the feed rolls 30, 30'.

Consequently, a bag placed on the table 7 will be picked up and moved forwardly by the pick-up member 10, so that the bag may be gripped and fed forwardly by the feed rolls 30, 30' immediately upon the initiation of the forward movement of the feed rolls. By this timing between the pick-up 10 and feed rolls 30, 30', the bag will be fed to the gripper rolls 40, 40' and their clamps 50, 50' while the gripper rolls are at the feeding station with the clamps open.

As shown in Figures 6 and 9, the clamps 50, 50' are tapered at their forward edges to define narrow leading edges 66, 66'. The taper of the edges 66, 66' is such that when the rolls 40, 40' are at their feeding station with the clamps 50, 50' open, the tapered surfaces of the leading edges 66, 66' will substantially abut. In this position, the leading edges 66, 66' jointly form a point 67 for separating the top edges of the bag B as the bag is fed forwardly by the feed rolls.

Due to the fact that the bags B comprise several layers of paper, however, it is possible for the point 67 to separate the layers of paper rather than the sides of the bag. Accordingly, as shown in Figures 9 and 10, a dart 68 having a pointed head 69 and a forwardly protruding blade 70 is provided for separating the folded edges of the valve V and thereby bias the top edges of the bag B apart and guide them into the clamps 50, 50'. As shown in Figures 2 and 15, the dart 68 is carried by a gear segment 71 that is journaled on a pin 72 which is carried by the gripper roll 40. Gear segment 71 meshes with a gear segment 73 that is mounted around the shaft 41 and fixed to the frame 1 by brackets 74.

Thus, as the gripper roll 40 is rotated, the dart 68 is carried therewith by the pin 72 and is itself rotated about the pin 72 by the inter-engaging gear segments 71 and 73. By this arrangement, the dart head 69 is moved rapidly to and from the feeding station to avoid interference with the movement of the bag B as it is carried forward or being withdrawn by the gripper rolls 40, 40'. The gripper rolls 40, 40' are each provided with a dished portion 75, 75' between its side and periphery and adjacent the clamps 50, 50' to accommodate the dart head 69 and the separated folds V of the bag B.

Simultaneous with the feeding of the bags B to and from the sleeving station, the machine is adapted to form individual sleeves from a sleeve strip and apply the sleeves to the valve portion V at the sleeving station. Referring now to Figures 1, 4 and 11, a roll R of sleeve strip S may

conveniently be mounted on a bracket 80 extending laterally from the frame 1. The sleeve strip S passes from the roll R to a guide roller 81 and along the length of an auxiliary frame 82 which is fixed to the side of the frame 1.

The sleeve strip S extends from the roller 81 around a guide plate 83 and behind a pair of spaced platen-forming rollers 84 to a between a pair of draw rolls 85 and 85'. As the strip S passes the platen rollers 84, it is periodically engaged by paste-applying wipers 86 which are carried by a roll 87. The paste-applying wipers 86 are spaced on the roll 87 and the latter is rotated in accordance with the movement of the sleeve strip S so as to apply a strip of paste to only one sleeve area at a time.

The wipers 86 are supplied with paste by engagement with a paste drum 88 housed within a paste pan 89 carried by the auxiliary frame 82. The roll 87 is positioned relative to the platen rollers 84 so that the wipers 86 engage the sleeve strip S at a point therebetween, and the paste-applying edge of the wipers 86 will move through a plane coinciding with or slightly within the plane of the platen rollers 84. Consequently, the wipers 86 will positively engage the surface of the sleeve strip S without undue pressure that would smear the paste because the strip may give slightly between the platen rollers 84.

It is desirable that the strip of paste applied to the sleeve strip be relatively narrow, and in practice, it has been found that a paste strip of about one-eighth of an inch in width is most satisfactory. In order to accomplish this, the wipers 86, as best shown in Figure 12, constitute a thin strip of material, preferably rubber, which has a paste-applying edge 90 that is cut by a plurality of spaced slots 91 which individually open into circular apertures 92.

It has been found that in contacting the paste drum 88, the paste-applying edge 90 may pick up an excess of paste which will flow into the slots 91 and be stored in the apertures 92 to maintain a supply of paste to be applied to the sleeve strip. Conversely, upon contacting the sleeve strip, the wipers 86 are slightly compressed, which causes a squeezing of the paste from the apertures 92 and through the slots 91 to the edge 90 to be applied thereby to the sleeve strip. As the paste is applied to the sleeve strip in a vertical plane, the fluid paste tends to flow down the edge 90, but this flow is interrupted by the slots 91, so that an even quantity of paste is applied throughout the height of the strip S.

In order to supply paste to the wipers 86, the paste drum 80 must also be vertical, as best shown in Figure 13. To provide an even supply of paste to the drum, it has been found that the upper end 93 of the drum 88 may be cupped to receive a supply of paste from a supply tube 94. The paste overflows from the cup 93 evenly around the top edges and down the sides of the drum 88, so that the entire periphery of the drum has an equal supply of paste. The paste flows down the drum 88 and is collected in the bottom of the paste pan 89 to be withdrawn by a discharge pipe 95. The paste is delivered by the pipe 95 to a tank 96, from which it is withdrawn through a pipe 97 by a pump 98 and fed thereby back through the supply pipe 94, as best shown in Figure 4.

As the bottom of the paste pan 89 may become filled with paste, the lower bearing for the paste drum 88 must be elevated. This is accomplished by providing the drum 88 at its lower end with an axial recess 99 which fits around an upstanding sleeve 100 fixed to the bottom of the paste pan 89 and adapted to support a bearing 101 at its top for the accommodation of the drum shaft 102. The top of the upstanding sleeve 100 is spaced above the bottom of the pan 89 a distance greater than the normal level of the collected paste in pan 89. The upper end of the shaft 102 extends upwardly from the center of the overflow cup 93 and is journaled in a bearing 103 mounted on top of the paste pan 89.

The draw roll 85 is provided with axially extending grooves 104 in spaced relationship in its periphery. These grooves 104 are of a size and spacing to straddle the strip of paste on the sleeve strip S. In actual practice, two of the grooves 104 are positioned diametrically in the roll 85. In addition, two of the paste wipers 86 are positioned diametrically of the roll 87. The rolls 85 and 87 are arranged so that their grooves 104 and wipers 86 are angularly coincident on their respective axes and these rolls are driven in timed relationship.

Furthermore, it is necessary that the sleeve strip S be advanced intermittently to permit the application of the

ultimately formed individual sleeves to the valves V at the sleeving station. Consequently, the drive for the sleeve mechanism, as best shown in Figures 1 and 4, is taken from the auxiliary drive shaft 18 by means of a bevel gear 105 which engages a complementary bevel gear 106 that is fixed on a vertical shaft 107 which is journaled in the auxiliary frame 82. The vertical shaft 107 carries a Geneva pin 108 for cooperation with a Geneva gear 109 that is fixed to a second vertical shaft 110.

A chain 112 is trained about a sprocket 111 on the shaft 110 and about a sprocket 113 fixed on the shaft 114 of the draw roll 85, as best shown in Figure 4. A gear 116 is fixed on the draw roll shaft 114 and engages a gear 116' on the shaft 114' of the draw roll 85', and also engages an idler gear 117 on an idler shaft 118. The idler gear 117 engages a gear 119 on the shaft 120 of the paste-applying roll 87 and the gear 119 engages a gear 121 on the paste drum shaft 102. Thus, the draw rolls 85, 85', the paste-applying roll 87 and the paste drum 88 are intermittently driven by the Geneva gear 109, and the paste straddling draw roll 85 and the paste-applying roll 87 are driven in the same direction and at the same speed through the idler gear 117.

In addition to the axial groove 104, the draw roll 85 is also provided with a centrally positioned annular groove 122, and the draw roll 85' is provided with a centrally positioned annular blade 123 to nest within the groove 122. As the sleeve strip S passes between these draw rolls 85, 85', the blade 123 will impress the sleeve strip into the groove 122 and form a scored line centrally of the sleeve strip S along its length to facilitate the folding of the ultimate sleeve when it is applied to the valve V.

Whereas the roll 85 is preferably a solid roller, due to the fact that the sleeve strip passes around it, the draw roller 85' need not be solid but may comprise three spaced discs, as shown, as its sole function is to score the sleeve strip and to provide the necessary friction between the sleeve strip and the draw roller 85. Consequently, the draw roller 85' is, preferably, adjustably mounted by bolts 124 and spring mountings (not shown) to be resiliently biased toward the draw roller 85.

The sleeve strip S is turned at right angles by the draw rolls 85, 85' to be fed across the front of the machine to the sleeving station, as best shown in Figures 1, 11, 14 and 15. From the draw rolls 85, 85' the sleeve strip extends through a fixed guide 125 to a cutting station 126. A stationary blade 127 is fixed to the end of the stationary guide 125 at the cutting station 126, and a movable blade 128 is mounted opposite the fixed blade 127. The movable blade is periodically operated to cut the sleeve strip S into individual sleeves. Beyond the cutting station 126, the sleeve strip S passes to a second fixed guide 129 which supports the individual sleeve at the sleeving station.

Referring now to Figures 14 and 15, it will be seen that the fixed sleeve guide 129 is rigidly supported by an upright frame 130 that is spaced in front of the frame 1 by brackets 131. The guide 129 is positioned with its outer edge 132 immediately in front of the edge of the valve V when it is spread in sleeving position by the rolls 40, 40'. Immediately in front of the edge 132 and in the same plane is a folding blade 133 that is fixed to the diametrical face of a semicircular half shaft portion 134 of a shaft 135 that is journaled in bearings 136 supported by the upright frame 130.

The fixed guide 129 is provided with guide channels 137 at its upper and lower edges, and these guide channels terminate in spaced relation with the edge 132 to accommodate gripper pads 138 carried by arms 139 which are fixed to a vertical shaft 140 journaled in bearings 141 that are also supported by the upright frame 130. At each movement of the draw rolls 85, 85', the leading edge of the sleeve strip is advanced from the cutting station 126, between the fixed guides 125 and 129, to a position approximately overlying the free edge of the folding blade 133, as indicated in broken lines in Figure 14.

The sleeve strip is advanced to this position while the bag B is being moved by the gripper rolls 40, 40' from the receiving station to the sleeving station. As soon as the valve V is flattened at the sleeving station, as shown in Figures 8 and 15, the advance of the sleeve strip S is completed. Substantially simultaneously the cutting

blade 128 is moved to cut the individual sleeve from the strip and the gripper pads 138 are swung to engage the sleeve strip and clamp it against the guide 129. Immediately thereafter the shaft 135 is rotated to swing the blade 133 around behind the edge of the flattened valve V and thereby fold the end of the sleeve S around the edge of the valve V.

To accomplish this swinging action of the blade 133, the half segment 134 of the shaft 135 is actually slightly less than half of the shaft, so that the axis of the shaft lies substantially in the plane of the face of the guide 129 and the folding blade 133 and between the adjoining edges of the guide and blade. By this arrangement, the blade 133 passes through a revolving path rather than a strict rotation, and consequently, its position at the opposite points of its path lies in two distinct planes which are spaced substantially the thickness of the bag and the folded sleeve, as best shown in Figure 17.

As soon as the folding blade 133 is swung around to fold the end of the sleeve and lightly presses the folded edge of the sleeve against the inner surface of the valve to assure adherence of the paste on the sleeve to the valve, the rotation of the blade 133 is reversed and it is swung back to its initial position. The gripper pads 138 are then swung away from the guide 129 to release the sleeve, and the reverse movement of the gripper rolls 40, 40' is initiated.

Simultaneous with the reversal movement of the gripper rolls 40, 40', a horizontal creasing blade 142 moves through a slot 143 in the face of the guide 129 and abuts the sleeve along the line scored by the draw roll knife 123 to initiate the folding of the sleeve and the valve V along their centers. The creasing blade 142 is carried by a bar 144 that is supported by a rack bar 145 extending at right angles and mounted in a slideway 146 that is supported by the upright frame 130.

The sleeve-forming and folding mechanism is all operated in timed relation to the movement of the sleeve and the bag by a drive system from the vertical shaft 107 which is driven by the auxiliary shaft 18. The vertical shaft 107 (Fig. 4) carries a sprocket 150 which is connected by a chain 151 with a sprocket 152 that is fixed to a vertical shaft 153 mounted on the front end of the auxiliary frame 82. Therefore, the shaft 153 is constantly driven, whereas the sleeve handling mechanism is intermittently driven through the Geneva gear 109.

It may be noted that according to the arrangement shown, the constantly driven shaft 153 will rotate once for each individual sleeve. On the other hand, the intermittently driven shafts 120, 114 and 114' respectively carrying the paste applying roll 87 and the draw rolls 85, 85' rotate once for each two individual sleeves. In other words, they pass through one-half of a revolution during each intermittent movement and for each individual sleeve.

A cam 154 on the constantly driven shaft 153 carries a trip finger 155 for operating a switch (not shown) that controls a solenoid 156 having a spring-biased core 157 that carries the cutting blade 128 on an extension 158. Thus, as the constantly driven shaft 153 rotates in timed relation with the intermittent movement of the draw rolls 85, 85', the trip 155 engages and closes the switch to energize the solenoid 156 immediately upon the cessation of each intermittent movement of the sleeve strip S and draw rolls 85, 85'.

Simultaneously with, or even before, the operation of the cutting blade 128, the gripper pads 138 are moved to clamp the sleeve S in the guide 129, as best shown in Figures 14 to 18. The gripper pads 138 are operated by the shaft 140 through their arms 139 by a crank arm 160 fixed to the shaft 140, that is connected by a pin 160' with a rod 161 to a cam 162 fixed on the constantly rotatable shaft 153. The cam 162 may be in the form of a crank or the like, but preferably comprises an organization similar to the reversible cams for driving the feed and gripper rolls, wherein an enlarged loop on the end of the rod 161 surrounds the shaft 153 and carries a cam-following pin inserted in a cam groove in the face of the cam 162.

Immediately upon the clamping of the sleeve by the pads 138, the shaft 135 is rotated to swing the blade 133 to fold the end of the sleeve. The movement of the shaft 135 is effected by a gear 163 secured on its lower end in engagement with a rack 164 that moves through a slideway 165 that is mounted on the frame 130. This

rack is connected by a pin 166 with a lever 167 pivoted on a pin 168 that is journaled in a bracket 169 that is mounted on the upright frame 130. The opposite end of the lever 167 is pivotally connected by a pin 170 with a rod 171 that is operatively connected at its opposite end with the cam 154 which carries the trip 155. The cam connection between the cam 154 and rod 171 preferably also comprises the same type of cam drive that has been previously described with respect to the cam 162 and the feed and gripper roll cams.

The cam 162 is arranged to pull the rod 161 to force the gripper pads 138 against the guide 129 to clamp the sleeve S and to hold that position while the cam 154 pulls the rod 171 to drive the rack 164 to revolve the folding blade 133 through its folding path and then back to its original position. When the folding blade 133 is returned to normal position, the cam 162 moves the rod 161 to swing the gripper pads 138 away from the guide 129 to free the sleeve.

Obviously, the movement of the gripper pads 138 and of the folding blade 133 must be carefully regulated or controlled to preclude excessive movement that would be damaging. It has been found that the easiest way to effect this control is to connect the rods 161 and 171 respectively with the crank 160 and lever 167 by resilient lost-motion members 185 which comprise, as best shown in Figure 19, a sleeve portion 186 closed at one end, from which an apertured ear 187 extends for the reception of the pivot pins 160' or 170. The end of the connecting rod 161 or 171 has a collar 188 fixed thereto and is inserted in the sleeve portion 186. A spring 189 surrounds the rod 161 or 171 for abutment at one end against the collar 188 and at the other by a sleeve 190 fixed to and closing the open end of the sleeve portion 186. Thus, when the rods 161 and 171 are pulled to operate the pads 138 and blade 133, any excessive movement is taken up by the springs 189.

Immediately upon the freeing of the sleeve, the creasing blade 142 is moved against the scored line of the sleeve to initiate the folding of the sleeve and valve. The creasing blade 142 is reciprocally moved by its slide rack 145 which engages a gear 172 that is fixed on a shaft 173 that is journaled in bearings 174 in the slide-way 146 and a bearing 175 supported by the upright frame 130. The gear 172 is mounted on the shaft 173 within the slideway 146.

A gear 176 is fixed to the upper end of the shaft 173 and is engaged by a curved rack 177 which is carried on the end of a lever 178 that is pivoted by a pin 179 on the main frame and carries at its opposite end a cam-following roller 180 that cooperates with a cam 181 mounted on the constantly driven shaft 153 and carrying a cam hump 182. The lever 178 is normally biased to one extreme of its movement by an integral arm 183 that is anchored by a spring 184 to the main frame 1. Thus, as the cam 181 rotates, its hump 182 will engage the follower 180 and pivot the arm 178 to swing the rack 177 and move the creasing blade 142 forwardly against the sleeve and then immediately retract the blade 142 by the action of the spring 184 upon the passage of the cam hump 182 past the follower 180.

Simultaneous with the operation of the creasing blade 142, the gripper rolls 40, 40' are started through their reverse movement from the sleeving station to the feeding station to withdraw and discharge the sleeved bag and receive the succeeding bag. As the bag is withdrawn by the feed rolls 30, 30' from the gripper rolls 40, 40', the edges of the bag are moved together by the clamps 50, 50' and the folds of the valve V and sleeve S are flattened.

As the bag is withdrawn, the flattened folds of the valve V and sleeve S are smoothed as the bag leaves the gripper rolls 40, 40'. The folds of the bag are first lightly smoothed by a pair of small rollers 191, 191' that are supported adjacent the feeding station of the gripper rolls 40, 40' by a pair of brackets 192, 192' that are mounted on the frame 1, as best shown in Figures 1-3. The bracket 192 is rigidly fixed to the frame 1 so that the roller 191 is stationarily positioned. The bracket 192' is pivotally mounted on the frame 1, however, so that the roller 191' may move vertically relative to the roller 191. The bracket 192' is journaled on a pin 193 and its free end is adjustable by a set screw 194 threadedly mounted on the frame.

After the bag folds are lightly smoothed by passing between the rollers 191, 191', it is then finally smoothed

as it passes through and is discharged from the feed rolls 30, 30' by a pair of smoothing rolls 195, 195' that are coaxially mounted with the feed rolls 30, 30' on the shafts 31, 31', as best shown in Figures 1-3. The smoothing rolls 195, 195' are slightly smaller in diameter than the feed rolls 30, 30' to accommodate the thickness of the folds. In addition, the smoothing roll 195' is frictionally driven to permit slippage and prevent jamming.

As best shown in Figures 32 and 33, the smoothing roll 195 is in fixed relation to its shaft 31, whereas the roll 195' has a central bore 196 that freely surrounds its shaft 31' and permits movement relative thereto and thereby accommodating variations in the thickness of the bag and valve folds. The roll 195' has an end face 197 for frictionally engaging a clutch element 198 carried by the adjacent feed roll 30'. The roll 195' is biased toward the clutch elements 198 by an end plate 199 fixed on the shaft 31' and which supports springs 200 that are seated in sockets 201 in the adjacent end of the roll 195'. Thus the springs 200 bias the roll 195' against the clutch element 198 and also tend to form a driving connection with the roll 195'. Therefore, the smoothing rolls, through the resilient friction drive and variation in spacing, permit a certain amount of slippage relative to the bag therebetween. With bags of certain kinds of paper, the spring 200 may be eliminated and the weight of the roll 195' by hollowing it out and filling with lead. This creates a certain amount of drag and effects an ironing of the bag folds.

As the operation of the individual elements of the machine has been set forth in conjunction with the description thereof, the following résumé of the operation will be limited to the broad functioning of the machine to more clearly point out the specific steps performed by the machine as well as the timed relation of these steps. Referring first to the bag handling mechanism, reference will be made to the schematic diagrams of Figures 20 to 25, and secondly, to the sleeve handling mechanism, reference will be made to Figures 11 and 26 to 30, the final sleeved bag being shown in Figure 31.

Referring to Figure 20, a bag B1 is at the sleeving station, it having had a sleeve attached to its valve, and the creasing blade 142 is about to be operated and the feed rolls 30, 30' and gripper rolls 40, 40' are stationary, but are about to be started in their reverse movement. A bag B2 has been placed by the operator on the feed table 7 and is awaiting the pick-up member 10. The pick-up 10 and drive rolls 23, 23', 23'' are constantly driven, whereas the fed rolls 30, 30' and gripper rolls 40, 40' are reversibly driven with intermediate stationary periods but with the feed rolls 30, 30' having longer drive periods than the gripper rolls 40, 40' and without an actual stationary period when discharging and receiving bags as they are immediately reversed.

Referring now to Figure 21, it will be seen that the parts and bags are in substantially the same position as in Figure 1. The feed rolls 30, 30' and gripper rolls 40, 40' are in their reverse movements and are withdrawing the bag B1, the creasing blade 142 having moved forward and is about to be retracted. The sleeved valve V of the bag B1 is being folded and the dart 68 is being moved toward the feeding station. Meanwhile, the pick-up 10 has picked up the bag B2 and fed it to the drive rolls 23, 23' to start another cycle of the bag handling mechanism.

Referring to Figure 22, the gripper rolls 40, 40' have reached the feeding station, their clamps 50, 50' being open and having released the bag B1. The creasing blade is completely retracted and the dart 68 is at the feeding station. The bag B1 is about to be discharged by the feed rolls 30, 30' which are still in their reverse movement and has entered the drive rolls 23, 23'' to be discharged from the machine. Meanwhile, the bag B2 has been picked up by the member 10 and driven by the drive rolls 23, 23' so that its front end is approaching the feed rolls 30, 30'.

In the next immediate step, shown in Figure 23, and corresponding to the position of Figure 2, the bag B1 has been discharged and the bag B2 picked up by the feed rolls 30, 30' which have immediately reversed from their reverse movement and are now in their forward movement. It will be recalled that the movement of the pick-up 10 and the drive rolls 23, 23' is correlated with that of the feed rolls 30, 30' so that the front end of a bag will reach the feed rolls 30, 30' substantially at or just

prior to their reversal from discharge to feeding movement. During this time, the gripper rolls 40, 40' and dart 68 remain stationary at the feeding station, the clamps 50, 50' remaining open.

The feed rolls 30, 30' feed the bag B2 forwardly to the feeding station between the gripper rolls 40, 40' where the dart 68 spreads the folds of the bag to guide its edges into the clamps 50, 50'. The gripper roll drive is coordinated with the feed roll drive through the main shaft 3, so that the gripper rolls 40, 40' start to move forwardly immediately upon the feeding of the bag to the clamps 50, 50' at the feeding station. As soon as the gripper rolls 40, 40' start their forward movement, the dart 68 is rapidly retracted and the clamps 50, 50' are immediately closed, as shown in Figure 24, where the bag B2 is being spread as it is moved from the feeding station to the sleeving station. Meanwhile, the bag B1 is being discharged by the drive rolls 23, 23'' and another bag B3 has been placed by the operator on the feed table 7 and is awaiting the pick-up 10.

As soon as the bag B2 is moved to the sleeving station, both the feed rolls 30, 30' and the gripper rolls 40, 40' stop and remain stationary during the sleeving operation, as shown in Figure 25. The dart 68 and creasing blade 142 are completely retracted. At this time, the preceding bag B1 is discharged from the drive rolls 23, 23'' and the succeeding bag B3 is about to be picked up by the member 10. As soon as the sleeving operation is completed, the cycle is repeated, starting with the operation shown in Figure 20.

During the time that a bag is being removed from and another bag fed to the sleeving station (Figures 21-24), the sleeve forming mechanism (Figures 11, 26 and 27) is being operated. While the bag is at the sleeving station (Figures 25 and 20), the sleeve applying mechanism (Figures 26-30) is being operated.

Referring now to Figure 11, the sleeves are formed from a strip S that is supplied from a roll R. The strip S is guided across the platen rollers 84 which support the strip in a vertical plane for the reception of a vertical strip of paste P transverse the sleeve strip. The paste is applied by one of the wipers 86 carried by the roll 87. The wiper 86 contacts the sleeve strip at a point midway between the platen rollers 84, so that the sleeve strip can give between the platen rollers 84 and prevent an excess of paste. The strip of paste P is preferably about one-eighth of an inch in width.

From the platen rollers 84, the pasted sleeve strip S passes around the draw roll 85 and between this roll and the resiliently supported draw roll 85'. One of the longitudinal grooves 104 in the draw roll 85 straddles the paste P as the strip S passes around the draw roll, so that the paste is not smeared. As the strip S passes between the draw rolls 85, 85' the blade 123 of the roll 85' presses the center of the strip into the annular groove 122 of the roll 85 to score a creasing line C longitudinally of the strip S.

From the draw rolls 85, 85' the creased and pasted sleeve strip S passes through the cutting station 126 to the sleeving station behind the gripper pads 138 and against the folding blade 133 in front of the gripper rolls 40, 40', as best shown in Figures 11, 26 and 27. An individual sleeve S' is cut from the end of the sleeve strip S, applied to the valve V of a bag at the sleeving station, and then the bag with the sleeve is withdrawn. The sleeve strip S is advanced intermittently during the movement of the bags from and to the sleeving station.

Upon the withdrawal of a bag from the sleeving station by the feed roll 30, 30' and gripper rolls 40, 40' and the retraction of the creasing blade 142 (Figure 22), the leading edge E of the sleeve strip S is advanced from the cutting station 126 toward the sleeving station. As the strip S advances, the end E passes behind the gripper pads 138 which are open, as shown in Figure 26. The end advances until its edge E substantially coincides with the edge of the folding blade 133, as shown in Figure 27. At this position, the advancement of the strip S stops as it is at the sleeving station.

When the strip S reaches the sleeving station, the gripper pads 138 are closed and the cutting blade 128 is moved through the cutting station 126 by the sole-noid 156 to sever the individual sleeve S' from the sleeve strip S, as shown in Figure 27. It should be noted that the sleeve strip is cut by the blade 128 immediately in front of the paste strip P, so that the paste

P is adjacent the edge E, as shown in Figures 26 and 27. Furthermore, the cutting blades 127, 128 are inclined so that the end edges E and E' are at an inclination rather than perpendicular to the longitudinal edges 5 of the sleeve S'.

Substantially simultaneous with the cutting of the sleeve S' (Figure 27), a bag is moved to the sleeving station (Figure 25). When the bag is at the sleeving station with its valve V flattened, as shown in Figure 8, 10 and a sleeve is at the sleeving station, the sleeve S' is directly in front of the valve V, as best shown in Figures 11 and 17, with the leading edge E of the sleeve S' extending beyond the edge of the valve V. The edge E of the sleeve S' substantially coincides with 15 the outer edge of the folding blade 133, as shown in Figure 27, whereas the edge of the valve V substantially coincides with the inner edge of the folding blade 133, indicated in broken lines.

As soon as the valve V is spread and the sleeve S' 20 is positioned at the sleeving station (Figure 27), the shaft 135 is rotated to revolve the folding blade 133 which folds the edge portion E of the sleeve S' around the edge of the valve V and lightly presses it against the rear surface of the valve, as shown in Figure 28. 25 The paste P is on the folded edge portion E so that the fold is secured to the rear or underside of the valve V.

The shaft 135 is then reversed and the blade 133 30 revolved back to its original position, the fold E remaining folded and secured to the underside of the valve V, as shown in Figures 29 and 11. Simultaneous with the return of the folding blade 133, the gripping pads 138 are swung to open position to release the sleeve S' (Figures 29 and 11).

The creasing blade 142 is then advanced from its 35 retracted position (Figures 25 and 11) to initiate the folding of the sleeve S' and valve V, as shown in Figures 20 and 30, the creasing blade 142 engaging the sleeve S' along the scored creasing line C to push the sleeve S' from the open gripper pads 138. Simultaneous with the advance of the creasing blade 142, the gripper rolls 40, 40' start their reverse movement (Figures 21 and 30) to withdraw the bag B.

Of course, as the bag is withdrawn and discharged (Figures 21 and 22) the folds of the valve V and sleeve 40 S' are smoothed by the opposed rollers 191, 191' and rolls 195, 195', so that the discharged bag appears as shown in Figure 31. It will be noted that the inclined end edge E' of the folded sleeve S' provides a flap F on one side of the sleeve which protrudes beyond the end edge of the other side of the sleeve. This flap F facilitates opening the end of the sleeve for filling when the sleeve and bag are closed, as by stitching along the dotted line L.

It will be noted that the parts in Figures 26 through 55 30 are exploded in comparison to their actual positions as shown in Figures 14 through 16, in order to preclude interference in illustrating the function and operation of the various parts. Moreover, although the adhesive employed for forming the strip P is referred to as 60 paste, it will be understood that any suitable or desired adhesive, such as glue or cement, may be employed. Furthermore, although the gripper rolls 40, 40' are shown as complete rolls or wheels, in actual practice it may be preferable to employ substantially semi-circular or half wheels to save material and decrease weight as well as partially eliminating inertia in the starting and stopping of the rolls.

Various modifications of the different elements of the 70 machine may be incorporated to effect desired results, depending upon the conditions encountered, such as the timing of the movements, the weight and size of the bags and the quality of the paper employed in both the bags and the sleeve strips. For instance, in order to vary the timing of the feed rolls 30, 30' and the gripper rolls 40, 40', the cam grooves 46 and the cams 37 and 37' may be varied in size and contour. Obviously, however, this would entail a great deal of work and require several sets of cams having different cam grooves therein. In order to readily facilitate the adjustment of 75 the timing of the feed and gripper rolls, the cams 37 and 37' may be modified and/or the rack bars 35, 35' may also be modified.

Referring now to Figures 34 and 35, a modification 80 of the cams is shown as comprising two coinciding and mating discs 37a and 37b. The disc 37b is fixed on the

main drive shaft 3 and is provided with a dovetail 202 diametrically on its surface, whereas the disc 37a has a groove 203 for sliding reception of the dovetail 202 and, in addition, this disc is provided with a central diametrical slot 203' parallel with the groove 203 for the reception of the main drive shaft 3 and to accommodate sliding movement between the discs 37a and 37b. The disc 37b is provided with set screws 204 or other suitable clamping means. By this arrangement the timing of the drive and feed rolls may be varied by adjusting the relative position of the discs 37a and 37b and thereby advance or delay the timing of the operation to a degree to vary the speed of the movement. In other respects this modified drive is identical to that previously described and shown in Figure 5, in that the rack bar meshes with the gear 34' mounted on the gripper roll shaft 41 and includes a cam follower 36' having a pin 45 for riding in the cam groove 46 and including a loop 43 for straddling and riding along a sleeve or roller 44 mounted on the main drive shaft 3. Obviously, this structure may be employed for both the feed and gripper rolls so that the gear 34 and shaft 40 may be substituted for the gears 34' and shaft 41 shown in these figures.

A modification of the rack drive is shown in Figure 36 wherein, for purposes of illustration, the ordinary cam 37' is shown. However, the split cam 37a-37b may be substituted therefor. According to this modification, the loop 43 of the cam follower 36' is disposed more or less vertically and comprises an arm 35a rigid therewith, which is pivotally connected by a pin 35b with a clamp arm 35c. A bell crank lever 205 journalled on a pivot 206 is provided with a lever arm 207 to be adjustably secured to the cam follower arm 35c, as by bolts 208. The bell crank 205 also includes an arm 209 having a segmental rack 210 disposed transversely of its end for meshing with gear 34'. By this arrangement the cam follower 36' is moved up and down by its pin 45 riding in the cam groove 46. As the cam follower 36' is moved, its arm 35a raises and lowers its arm 35c and thereby reciprocally pivots the bell crank 205 to reversibly drive the shafts 40 or 41, as the case may be. This modification has the advantage of facilitating not only the variation in time, but also the speed by the adjustment of the bell crank lever arm 207 longitudinally of the cam follower arm 35c to thereby vary the arc of pivotal movement and the speed and duration of the drive.

When the bag is formed of relatively soft paper or of thinner ply, or when the valve V is relatively small, there being quite a variation in the folds of the valves in the bags, it has been found advantageous to provide a dart with each of the groove rolls 40 and 40', in view of the fact that the protruding dart head 69 follows the movement of the gripper rolls and the valve as they move to sleeving position. Consequently the dart head, overlying the folded edge of the valve, helps to hold the valve fold in position and prevent its collapsing during the opening movement, which results in a loose, uneven valve at the sleeving station. To accomplish this, it has been found that the dart head 69 may be advantageously divided, with a part of the head carried by each roll, as shown in Figures 37 and 38. According to this modification, the roll 40 is provided with a fixed gear segment 73 about its shaft 41 and a pivot 72 carried by the roll and rotatably supporting the gear segment 71 in mesh with the fixed gear segment 73, substantially identical to the construction previously described. In addition, the roll 40' is provided with a fixed gear segment 73' around the shaft 41' and carries a pivot 72' upon which a gear segment 71' is mounted in engagement with the fixed gear 73'. Each of these segments 71 and 71' carry dart segments 68a and 68b, respectively, which have a segmental dart head 69a and 69b, respectively. The dart head segment 69a preferably carries the extended tongue 70 and is provided with an upper or outer offset edge 211 for mating with a comparable edge 211' carried by the dart head 69b, as shown in Fig. 37. Thus a curved valve engaging portion of the dart head is provided for each roll to remain in engagement with the valve folds during the opening and spreading of the valve. With some types of bags it is preferable to release the edges of the bag from the clamps 50 and 50' immediately upon the insertion of the sleeve and before the gripper rolls 40, 40' are

driven through their reverse movement. A preferred means for accomplishing this function is shown in Figures 39 and 40, wherein it will be seen that the clamps 50, 50' are carried by bars 52' that extend diametrically through the gripper rolls 40, 40', each of these bars having a reduced neck portion 51 adjacent their respective clamps for sliding in a slot 51' in the flange 40a of the roll and a reduced portion 51a at the opposite end of the bar 52' and sliding through the slot 51' in the diametrical portion of the flange 40a to protrude beyond the periphery of the roll. The bars 52' are provided with cam following rollers 58 for cooperation with cams 59 having humps 60 for opening the clamps at the receiving station in the usual manner. In order to open the clamps at the sleeving station levers 215 and 215' are respectively positioned at the location of the protruding bar end 51a when the clamps are at the sleeving station. These levers 215 and 215' respectively are carried by pivots 216 and 216' that are journalled in the frame 1 and have cam following bars 217 and 217' fixed thereto. The cam following bars 217, 217' are each provided with a cam follower 218, 218' for cooperation with cams 219, 219', respectively having cam humps 220, 220', mounted on the main vertical cam shaft 153 in the auxiliary frame 82. The cam following levers 217, 217' are biased toward the cams 219, 219' by springs 221, 221' to normally retain the clamp operating levers 215, 215' in retracted position. As the cam shaft 153 is constantly rotated, the cam humps 220, 220' of the cams 219, 219' will periodically engage the cam followers 218, 218' to swing the lever arms 217, 217' against the tension of the springs 221, 221' and about their pins 216, 216' to swing their clamp operating levers 215, 215' against the extensions 51a of the clamp bars 52' to move the clamps 50, 50' away from their respective roll peripheries and thereby release the edges of the bag. Immediately upon the passing of the cam humps 220, 220' the springs 221, 221' retract cam levers 217, 217' to withdraw the clamp levers 215, 215' and permit the retraction of the clamps 50, 50' by their springs 57.

The sleeves may be formed of any suitable material, but a preferred material is a rather coarse, inexpensive crepe paper. Consequently it has been found that in some instances this crepe paper lacks sufficient inherent rigidity to maintain a vertical position within the guides 125 and 129 between the draw rolls 85, 85' and the sleeving station. In order to overcome any sagging of the sleeve strip through these guide rolls and particularly at the cutting station 126, it has been found desirable, in using such sleeve paper, to provide small drive rolls having threaded peripheries adjacent the cutting station so that the threaded peripheries act to separate the edges of the sleeve strip and stretch the sleeve paper. This construction is best shown in Figs. 41 to 44, wherein it will be seen that opposed upper rolls 225, 225' and lower rolls 226, 226' are respectively mounted on shafts 227, 227' which carry intermeshing gears 228, one of which is driven by a gear 229 mounted on a shaft 230 that carries a sprocket 231 which may be connected by a chain with the intermediate drive emanating from Geneva gear 109. The guide 125 is provided with slots 231 for the reception of the drive wheels 225, 226 and its guide channels 7, 137 are provided with slots or recesses 232 for the accommodation of the drive wheels 225, 225'. Thus the upper rolls 225 and 225' engage the upper edge of the sleeve strip and intermittently drive it forwardly, while the lower rolls 226, 226' engage the lower edge of the sleeve strip and likewise intermittently drive it forwardly. Furthermore, as best shown in Figure 41, the peripheries of the drive rolls are threaded and the upper and lower rolls are respectively arranged with their threads in opposite directions so that the upper rolls 225, 225' cooperate by means of their threads to tend to pull the sleeve upwardly, whereas the lower rolls 226, 226' are threaded to pull the lower edge of the sleeve downwardly so that the threads on the rolls cooperate to stretch the sleeve strip taut in a flat, vertical plane at the cutting station 126. Furthermore, as best shown in Figures 43 and 44, it has been found that the threaded rolls cooperate most effectively by providing the top rolls 225, 225' with threads of $\frac{1}{32}$ of an inch, having $\frac{1}{4}$ of an inch pitch, whereas the bottom rolls 226, 226' have threads of $\frac{1}{16}$ of an inch, with a three pitch or 3 to 1 inch. Why this variation of the threads of the rolls is more effective than

a uniform threading is not known, but actual practice has shown that this variation in threading is sometimes necessary in order to maintain an even tension on the sleeve strip.

It has been found in some types of bags that the valves V are folded over unevenly so that they are not stretched smoothly in a vertical plane when they are opened by the gripper rolls 40, 40' at the sleevng station. In order to overcome this difficulty and to fold the leading edge of the sleeve around the valve with greater efficiency, under such circumstances the folding blade may be modified in its structure and operation and may have a valve hold-down arm associated therewith, as best shown in Figures 45 through 52. According to this structure the folding blade 133' is supported by lugs 133a which are pivotally carried by crank arms 134' that are fixed on a shaft 135' that is journaled in bearing brackets 136' that are mounted on the upright frame 130. The shaft 135' has a crank arm 135a secured thereto and connected by a pivot 235 with a link 164' which, in effect, replaces the rack 164 and the previously described construction. The link 164' is connected by a pivot 166' with a lever 167' that is mounted by a pivot 168' to a bracket 169' that is fixed to the upright support 130. The cam rod 171 is operatively connected with a cam 154' mounted on the constantly driven cam shaft 153. The push rod 171 is connected with the lever 167' by a pivot 170', the only difference in the organization being that the push rod 171 is connected to the lever 167' between the ends of the lever to obtain a greater modification of the stroke. The cam 154' may be identical to the cam 154 previously described, with the exception that it has a cam hump 154a protruding from its periphery.

The folding blade 133' is provided with an angularly extending arm 133b that carries a cam following roller 236 that engages a cam surface 237 extending from the upper bearing bracket 136'. The cam follower 236 is retained in engagement with the cam 237 by a spring 238 fixed at one end to an arm 239 forming the upper part of the upper bearing bracket 136 and at the other end to the arm 133b of the folding blade 133'.

A valve hold-down arm 240 is fixed on a shaft 241 which is journaled in bearing portions 242 extending from the bearing brackets 136'. A crank 243 is fixed to the shaft 241 and is connected by a pivot 244 with a link 245 which in turn is connected by the pivot 246 with an elongated lever 247 that is pivoted on a shaft 248 on the main frame. Lever 247 carries at its opposite end a cam following roller 249 that is biased into engagement with the periphery of the cam 154' by a spring 250 that is anchored at one end to the lever 247 and at the other to a point 251 of the main frame.

By this construction the folding blade 133' and the valve hold-down arm 240 are both operated from the single cam 154' in timed relation. In normal or retracted position, as shown in dotted lines in Figure 45 and in full lines in Figure 52, the push rod 171 is withdrawn by the cam 154' and pulls the lever 167' which pulls the link 141', which in turn pulls the crank 145a and swings the crank 134' to retract the folding blade 133'. Similarly the spring 250 pulls the lever 247 toward the cam 154' and thereby pulls the link 245 to swing the crank 243 rearwardly and thereby swing the valve hold-down arm 240 beyond the edge of the valve. Upon the operation of the cam 154' the rod 171 is pushed forwardly, which pushes the lever 171' which pushes the link 154' to swing the crank 135a and consequently the cranks 134' to move the blade 133' to forward folding position. As the blade 133' swings forwardly, it is also pivoted angularly by the spring 238 pulling on its arm 133b and the angular movement of the blade is regulated by the cam follower 236 following the contour of the cam 237.

When the cam hump 154a engages the follower 249 it swings the lever 247 against the tension of the spring 250 and the lever 247 thereby pushes the link 245 which pushes the crank 243, which swings the valve engaging arm 240 against the flattened valve. As shown in Figure 47, an oversize valve V does not lie flat against the sleeve S' when it is spread to sleevng position by the gripper rolls 40, 40'. Consequently the valve presents an uneven edge and surface, which causes difficulty in folding the sleeve therearound. The arm 240, however, is swung inwardly so that its forked tines 240' and

shoes 240a engage and flatten the valve V, as shown in Figure 46.

The actual operation of the folding blade 133' is best illustrated in Figures 49, 50 and 51. In Figure 49 the retracted position of the blade 133' is shown in full lines. In this position it is level with the front surface of the upright frame 130 or, actually the guide 129, along which the sleeve S' is positioned, the end E of the sleeve extending beyond the edge of the upright frame and overlapping the blade 133'. The valve V is simultaneously spread and is positioned so that its vertical edge substantially coincides with the edge of the upright frame 130. Due to the fact that the valve may be oversize or undersize, it does not lie flat against the frame 130, but tends to bias therefrom. In this condition the movement of the folding blade 133' is initiated and it is moved and simultaneously angularly pivoted in the initial stage to the position shown in broken lines in Figure 1.

As its movement continues, the blade 133' is moved and further angled upwardly to the position shown in broken lines in Figure 50. During this movement the edge portion E of the sleeve S' is folded up against and slightly over the edge of the valve V. Upon further movement of the blade 133' it swings through a relatively flat arc and simultaneously moves forward to turn the end portion E of the sleeve S' back over the valve V, as shown in full lines in Figure 50. At about this point of the operation, the valve hold-down arm 240 is swung forward and engages or is engaged by the leading edge of the sleeve which is turned inwardly thereby.

By this arrangement, the sleeve is definitely folded around the edge of the valve, even though the valve may be lying in a rather uneven position. At the time that the arm 240 is swung into operative position, the blade 133' is moving downwardly and pivoting inwardly to the position shown in broken lines in Figure 51. As the movement continues, the arm 240 engages and flattens the valve V, and the blade 133' is swung inwardly and angled to lie flat against the edge portion E of the sleeve to fold and secure the edge portion to the back of the valve V. In the final position the blade 133' lies flat against the edge portion E of the sleeve and the shoes 240a are flat against the valve V, with the edge of the sleeve portion just under the heel of the shoes 240a. Obviously, upon being retracted, the blade 133' follows the same course of movement in the reverse order.

As soon as the blade 133' and the arm 240 are retracted, the creasing blade 142 is then advanced to initiate the folding of the sleeve and valve as previously described. It has been found with oversize or unevenly folded valves, however, that there is a possibility of their not folding properly but merely being crushed flat due to the reversal or flattening of the folds during the sleevng operation. In order to preclude this possibility, the creasing blade 142 may be supplemented by leaf springs 252 carried by the creasing blade rack arm 145 and extending vertically from above and below. By this arrangement, when the creasing blade 142 is advanced, the leaf springs 252 engage the outer portions of the sleeve and valve, as shown in Figure 48, and press them against the gripper rolls 40, 40' respectively, so that the opposed sides of the sleeved valve are retained smoothly against the gripper rolls and prevented from improperly folding.

Although certain specific embodiments of the invention are shown and described, it is obvious that many modifications thereof are possible. The invention, therefore, is not to be restricted except in so far as is necessitated by the prior art and by the spirit of the appended claims.

What we claim is:

1. A valved bag sleevng machine, comprising means for releasably gripping the opposite top edges of a bag to spread and flatten the valve forming fold of the bag, means for positioning a flat sleeve forming sheet in front of the flattened valve fold, means for securing the positioned sleeve forming sheet to the flattened valve fold, and means for folding the sleeve and valve as the bag is released by the gripping means, said gripping means including a pair of opposed rolls respectively carrying clamps that are spring biased closed, means for reversibly driving said rolls from a feeding position wherein

said clamps are substantially abutting to a sleeving position wherein said clamps are spaced to spread the valve fold, and cam means for opening said clamps when said rolls are rotated to the feeding position.

2. A machine as defined in claim 1, wherein said cam means is adjustable to regulate the angular position of clamp opening.

3. A valved bag sleeving machine, comprising means for releasably gripping the opposite top edges of a bag to spread and flatten the valve forming fold of the bag, means for positioning a flat sleeve forming sheet in front of the flattened valve fold, means for securing the positioned sleeve forming sheet to the flattened valve fold, and means for folding the sleeve and valve as the bag is released by the gripping means, said sleeve securing means comprising a pivotally mounted blade that is reciprocally movable through an arc for folding the end of the sleeve forming sheet around the edge of the valve forming fold.

4. A machine for sleeving valved bags, comprising a fixed sleeve holder, mechanism for spreading and flattening the preformed valve of a bag in front of said holder, means operative after the flattening of the preformed valve for attaching the sleeve in said holder to the flattened valve and thereafter releasing said sleeve and means operative upon the attachment and release of the sleeve for simultaneously refolding the valve and folding the sleeve therein said folding means comprising a creasing blade reversibly movable in a plane and through a slot in said fixed sleeve holder for abutting the center line of the sleeve sheet and valve fold to push the sheet and valve into the valve folded position.

5. A valved bag sleeving machine, comprising relatively movable gripping means for releasably gripping the opposite top edges of a bag adjacent the folds of the previously formed valve therein, means for moving said gripping means apart to spread and flatten the valve forming fold of the bag, means for forming and positioning a sleeve in front of said flattened valve fold, means for securing a positioned sleeve to the flattened valve forming fold, reversible means for feeding bags reciprocally to and from said gripping means, and means for folding and smoothing the sleeved valve as the bag is released by the gripping means and moved therefrom by said feeding means.

6. A valved bag sleeving machine, comprising means for releasably gripping the opposite top edges of a bag adjacent the previously formed valve therein to spread and flatten the valve forming fold of the bag, means for forming and positioning a sleeve in front of said flattened valve fold, means for securing a positioned sleeve to the flattened valve forming fold, means for feeding bags to and from said gripping means, and means for folding and smoothing the sleeved valve as the bag is released by the gripping means and moved therefrom by said feeding means, said gripping means including a pair of opposed rolls carrying clamps, said feeding means including opposed feed rolls for feeding a bag to and from said gripping rolls and pick-up means for feeding a bag to said feed rolls, and means for reversibly driving said feed and gripping rolls in timed relation and constantly driving said pick-up means in timed relation to said feed rolls.

7. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said clamps in spaced relation to open the bag and flatten the valve portion thereof, means for opening the clamps at the feeding station and closing the clamps substantially immediately upon leaving the feeding station, opposed feed rolls for feeding a bag to said gripper rolls and withdrawing the bag therefrom, means for reversibly driving said feed rolls in timed relation with said gripper rolls, drive rolls for supplying a bag to said feed rolls and for removing a bag therefrom, pick-up means for supplying a bag to said drive rolls, means for constantly driving said pick-up means to supply a bag at a rate of frequency so that a bag is supplied to said feed rolls substantially at the discharge of a preceding bag by

said rolls, and means for securing a sleeve to the flattened valve portion at the sleeving station.

8. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said clamps in spaced relation to open the bag and flatten the valve portion thereof, means for opening the clamps at the feeding station and closing the clamps substantially immediately upon leaving the feeding station, a dart movable in timed relation to and from the adjoining portions of said gripper rolls at the feeding station for separating the edges of the bag and respectively guiding them to said clamps, opposed feed rolls for feeding a bag to said gripper rolls and withdrawing the bag therefrom, means for reversibly driving said feed rolls in timed relation with said gripper rolls, constantly driven rolls for supplying a bag to said feed rolls and for removing a bag therefrom, pick-up means for periodically supplying a bag to said constantly driven rolls at a rate of frequency so that a bag is supplied to said feed rolls substantially at the discharge of a preceding bag by said rolls, and means for securing a sleeve to the flattened valve portion at the sleeving station.

9. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said

clamps in spaced relation to open the bag and flatten the valve portion thereof, means for opening the clamps at the feeding station and closing the clamps substantially immediately upon leaving the feeding station, a dart movable in timed relation to and from the adjoining portions of said gripper rolls at the feeding station for separating the edges of the bag and respectively guiding them to said clamps, opposed feed rolls for feeding a bag to said gripper rolls and withdrawing the bag therefrom, means for reversibly driving said feed rolls in timed relation with said gripper rolls, constantly driven rolls for supplying a bag to said feed rolls and for removing a bag therefrom, pick-up means for periodically supplying a bag to said constantly driven rolls at a rate of frequency so that a bag is supplied to said feed rolls substantially at the discharge of a preceding bag by said rolls, means for securing a sleeve to the valve portion of a bag supported at the sleeving station by said gripper rolls, relatively adjustable means adjacent the feeding station of said gripper rolls for initially smoothing the valve and sleeve as the bag is released by said gripper roll clamps, and frictionally driven smoothing rollers coaxial with said feed rolls for finally smoothing the valve and sleeve as the bag is discharged by said feed rolls.

10. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said clamps in spaced relation to open the bag and flatten the valve portion thereof, means for supplying a sleeve strip from a source of supply, rotatable paste-applying means for applying a strip of paste transversely of said sleeve strip, a pair of opposed rotatable draw rolls, one of said draw rolls having axially extending grooves in spaced relation to straddle the strips of paste on said sleeve strip and a central annular scoring groove, the other of said draw rolls having a central annular scoring blade for nesting with said groove to score the sleeve strip longitudinally, means for intermittently rotating said paste applying means and draw rolls to intermittently advance said sleeve strip, a fixed guide for receiving said sleeve strip from said draw rolls and extending to a position in front of said gripper rolls, means combined with said fixed guide for cutting said sleeve strip into individual sleeves, means for folding the leading edge of the guide-held sleeve about the edge of the valve portion of a bag supported at the sleeving station by said gripper rolls, means operative after the release of

the folded strip and during the reversal of said gripper rolls for creasing the valve and sleeve along the scored line of said sleeve and expelling said sleeve laterally from said fixed guide, and means for operating said cutting means, holding means, folding means and creasing means during the stationary periods between the intermittent driven periods of said sleeve strip and while said gripper rolls are at their sleeving station.

11. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said clamps in spaced relation to open the bag and flatten the valve portion thereof, means for supplying a sleeve strip from a source of supply, rotatable paste-applying means for applying a strip of paste transversely of said sleeve strip, means for supporting said sleeve strip in paste-receiving position, a pair of opposed rotatable draw rolls, one of said draw rolls having axially extending grooves in spaced relation to straddle the strips of paste on said sleeve strip and a central annular scoring groove, the other of said draw rolls having a central annular scoring blade for nesting with said groove to score the sleeve strip longitudinally, means for intermittently rotating said paste-applying means and draw rolls to intermittently advance said sleeve strip, a fixed guide for receiving said sleeve strip from said draw rolls and extending to a position in front of said gripper rolls, means combined with said fixed guide for cutting said sleeve strip into individual sleeves, said cutting means being positioned to cut at an angle adjacent each paste strip so that the paste strip is at the leading edge of each individual sleeve, means for releasably holding each sleeve rigidly in said fixed guide, means for folding the paste strip carrying leading edge of the rigidly held sleeve about the edge of the valve portion of a bag supported at the sleeving station by said gripper rolls, means operative after the release of the folded strip and during the reversal of said gripper rolls for creasing the valve and sleeve along the scored line of said sleeve and expelling said sleeve laterally from said fixed guide, and means for operating said cutting means, holding means, folding means and creasing means during the stationary periods between the intermittent driven periods of said sleeve strip and while said gripper rolls are at their sleeving station.

12. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said clamps in spaced relation to open the bag and flatten the valve portion thereof, means for supplying a sleeve strip from a source of supply, rotatable paste-applying means for applying a strip of paste transversely of said sleeve strip, means for supporting said sleeve strip in paste-receiving position, a pair of opposed rotatable draw rolls, one of said draw rolls having axially extending grooves in spaced relation to straddle the strips of paste on said sleeve strip and a central annular scoring groove, the other of said draw rolls having a central annular scoring blade for nesting with said groove to score the sleeve strip longitudinally, means for intermittently rotating said paste applying means and draw rolls to intermittently advance said sleeve strip, a fixed guide for receiving said sleeve strip from said draw rolls and extending to a position in front of said gripper rolls, means combined with said fixed guide for cutting said sleeve strip into individual sleeves, said cutting means being positioned to cut at an angle adjacent each paste strip so that the paste strip is at the leading edge of each individual sleeve, means for releasably holding each sleeve rigidly in said fixed guide, means for folding the paste strip carrying leading edge of the rigidly held sleeve about the edge of the valve portion of a bag supported at the sleeving station by said gripper rolls, means operative after the release of the folded strip and during the reversal of said gripper rolls for creasing the valve and sleeve along the scored line of said sleeve and expelling said sleeve laterally from said fixed guide, means for

operating said cutting means, holding means, folding means and creasing means during the stationary periods between the intermittent driven periods of said sleeve strip and while said gripper rolls are at their sleeving station, relatively adjustable means adjacent the feeding station of said gripper rolls for initially smoothing the valve and sleeve as the bag is released by said gripper roll clamps, and frictionally driven smoothing rollers coaxial with said feed rolls for finally smoothing the

5 valve and sleeve as the bag is discharged by said feed rolls.

13. A machine for inserting a sleeve in a valved bag, comprising a pair of opposed gripper rolls for receiving a valved bag therebetween and carrying clamps for gripping the opposed edges of the bag adjacent the valve thereof, means for reversibly driving said rolls to and from a feeding station with said clamps in substantially abutting relationship to a sleeving station with said clamps in spaced relation to open the bag and flatten the valve portion thereof, means for opening the clamps at the feeding station and closing the clamps substantially immediately upon leaving the feeding station, a dart movable in timed relation to and from the adjoining portions of said gripper rolls at the feeding station for separating the edges of the bag and respectively guiding them to said clamps, opposed feed rolls for feeding a bag to said gripper rolls and withdrawing the bag therefrom, means for reversibly driving said feed rolls in timed relation with said gripper rolls, 15 constantly driven rolls for supplying a bag to said feed rolls and for removing a bag therefrom, pick-up means for periodically supplying a bag to said constantly driven rolls at a rate of frequency so that a bag is supplied to said feed rolls substantially at the discharge of a preceding bag by said rolls, means for supplying a sleeve strip from a source of supply, rotatable paste-applying means for applying a strip of paste transversely of said sleeve strip, means for supporting said sleeve strip in paste-receiving position, a pair of opposed rotatable draw rolls, one of said draw rolls having axially extending grooves in spaced relation to straddle the strips of paste on said sleeve strip and a central annular scoring groove, the other of said draw rolls having a central annular scoring blade for nesting with said groove to score the sleeve strip longitudinally, means for intermittently rotating said paste applying means and draw rolls to intermittently advance said sleeve strip, a fixed guide for receiving said sleeve strip from said draw rolls and extending to a position in front of said gripper rolls, means combined with said fixed guide for cutting said sleeve strip into individual sleeves, said cutting means being positioned to cut at an angle adjacent each paste strip so that the paste strip is at the leading edge of each individual sleeve, means for releasably holding each sleeve rigidly in said fixed guide, means for folding the paste strip carrying leading edge of the rigidly held sleeve about the edge of the valve portion of a bag supported at the sleeving station by said gripper rolls, means operative after the release of the folded strip and during the reversal of said gripper rolls for creasing the valve and sleeve along the scored line of said sleeve and expelling said sleeve laterally from said fixed guide, means for operating said cutting means, holding means, folding means and creasing means during the stationary periods between the intermittent driven periods of said sleeve strip and while said gripper rolls are at their sleeving station, relatively adjustable means adjacent the feeding station of said gripper rolls for initially smoothing the valve and sleeve as the bag is released by said gripper roll clamps, and frictionally driven smoothing rollers coaxial with said feed rolls for finally smoothing the valve and sleeve as the bag is discharged by said feed rolls.

14. The method of sleeving a valved bag which comprises spreading the valve portion of a bag to substantially straighten the valve thereof, applying a sleeve-forming sheet to the outside of said straightened valve and with its ends extending beyond the inner and outer ends of said valve, folding the inner end portion of said sheet around the free inner edge of said valve, and simultaneously refolding said valve while folding said sheet inwardly along a median line to form a sleeve within said valve.

15. The method of sleeving a valved bag which comprises spreading the valve portion of a bag to substan-

5 tally straighten the valve thereof, with the free edge portion of the valve substantially in a plane perpendicular to the bag, applying a sleeve-forming sheet to the outside of said straightened valve and with its ends extending beyond the inner and outer ends of said valve, folding the inner end portion of said sheet around the free inner edge of said valve and securing the folded portion of said sheet to the back of said valve, and simultaneously re-folding said valve while folding said sheet inwardly along a median line to form a sleeve within said valve.

16. A machine for sleeving valved bags, comprising a fixed sleeve holder, means for feeding a sleeve to said holder, clamps for releasably holding a sleeve in said holder, means operative upon the feeding of a sleeve to said holder to actuate said clamps to hold the sleeve in said holder, mechanism for spreading and flattening the preformed valve of a bag in front of said holder, means for feeding a bag to said mechanism, means operative after the flattening of the preformed valve for attaching the sleeve in said holder to the flattened valve, means operative upon the attaching of the sleeve for actuating said clamps to release the sleeve from said holder, and means operative upon the attachment and release of the sleeve for simultaneously refolding the valve and folding the sleeve therein.

17. A machine for sleeving valved bags, comprising a fixed sleeve holder, means for intermittently feeding sleeves to said holder, clamps for releasably holding a sleeve in said holder, means operative upon the feeding of each sleeve to said holder to actuate said clamps to hold the sleeve in said holder, mechanism operative during the feeding and clamping of each sleeve for spreading and flattening the preformed valve of a bag in front of said holder, means operative after the flattening of the preformed valve for attaching the sleeve in said holder to the flattened valve, means operative upon the attaching of the sleeve for actuating said clamps to release the sleeve from said holder, means operative upon the attachment and release of the sleeve for simultaneously refolding the valve and folding the sleeve therein, and means for successively feeding valved bags to and from said valve spreading mechanism.

18. In a machine for inserting a sleeve in the previously-formed valve of a valved bag, the combination of means for supporting a valved bag with its pre-formed valve flattened and in a position to have a sleeve applied thereto, a member for supporting a section of sleeve-

5 forming material substantially parallel to and in front of the flattened valve, said member having a central longitudinal slot therein, mechanism for supplying a section of sleeve-forming material to said supporting member, means for scoring the section of sleeve-forming material along a median line before it is supplied by said mechanism to said member, means for applying the supported section of sleeve-forming material to the flattened valve, with the scored line substantially coincident with the central valve fold, and a blade movable through said slot in said member into momentary engagement with the applied sleeve section substantially along its scored line to break the sleeve section along the scored line and the valve along the center fold for initiating simultaneous re-folding of the flattened valve and folding the section of sleeve-forming material inwardly into the valve to form a sleeve within the valve.

19. A method of sleeving valved bags, which comprises forming a sleeve, positioning the sleeve in a flat condition at a sleeving station, feeding a valved bag longitudinally to the sleeving station with the valve and the leading end of the bag and with the longitudinal axis of the bag disposed perpendicular to the flat sleeve at the sleeving station, gripping at the sleeving station the leading end edges of the bag adjacent the valve folds, moving the gripped edges apart to spread and substantially flatten the valve in a position in front of and substantially parallel to the sleeve and substantially perpendicular to and extending substantially transversely of the bag, applying the sleeve to the substantially flat valve, and retracting the bag from the sleeving station while simultaneously refolding the valve and folding the sleeve into the valve.
